COVER FOR HATCHES, WAGGONS AND THE LIKE

Claude Lecomte, Fontenay aux Roses, France, assignor to
International MacGregor Organization (I. M. G. O.),
Casablanca, Morocco, a body corporate of Morocco

Application January 4, 1955, Serial No. 479,757

Claims priority, application France January 22, 1954

4 Claims. (Cl. 160—193)

The present invention relates to hatch-covers and more particularly to a cover arrangement for ships, hatchways, wagons and the like, or other purposes, which comprises a plurality of separate hatch-covers independent of the hatchway coaming edges and adapted to constitute an unbroken sheet closing the hatchway and to roll along the hatchway coaming during the hatchway closing and opening operations.

Hatchway-covers of this type are already known wherein the component elements are independent of each other and are operated separately. The purpose of this separate operation of the hatch-covers is to bring them by turns to a vertical position in a so-called stowage space provided accordingly at one end of the hatchway.

In other installations of same character the hatch-covers are interconnected through chains so that the complete assembly may be moved by operating a single control rope in both hold-closing and hold-opening directions. In this case, the hatch-covers fall fiercely from their vertical positions onto the runway.

In other known arrangements unbroken sheets of hingedly interconnected panels are used.

Now the arrangement forming the subject-matter of the present invention is characterised notably in that the separate and adjacent sections or elements constituting the hatch-cover are interconnected through pivot links, rods or levers adapted to transmit both tractive forces and end thrusts.

According to another feature of the invention, the points of pivotal attachment of a link, if considered in connection with a pair of adjacent hatch-cover elements, are positioned the one at the rear portion of the element remotest from the stowage space, and the other at an intermediate position—in the longitudinal direction—of the next element of the pair.

The arrangement according to the present invention offers the positive advantages of affording an unbroken movement of the interconnected hatch-cover elements, employing very simple actuating means, reducing the overall dimensions to a minimum, and, above all, requiring a stowage space of particularly small dimensions. In fact, the length of each hatch-cover section or element is no more a function of the vertical dimension of the coaming, as generally observed in some known arrangements.

On the other hand, the system according to this invention enables the hatch-cover to be operated at a much faster rate than any other known systems, particularly those incorporating independent elements.

Other features and advantages of the invention will appear as the following description of a few forms of embodiment of the invention, given by way of example with reference to the accompanying drawings, wherein:

Figure 1 shows diagrammatically in elevational view a ship's hatchway equipped with the hatch-cover arrangements of the present invention, the elements being shown in their closed conditions;

2

Figure 2 is a similar view showing the arrangement during the opening thereof;

Figure 3 is another view similar to Figs. 1 and 2 showing the hatch-cover in its open condition;

Figure 4 illustrates at a greater scale the method of mounting the links on the hatch-cover sections;

Figure 5 is a modified embodiment of the hatch-cover arrangement shown in its closed condition, and

Figure 6 is a similar view showing the same modified arrangement in its open condition.

In the embodiment illustrated in Figs. 1 and 3 of the accompanying drawing it is assumed that the hatch-cover system is adapted to close a hatchway shown diagrammatically in the form of a coaming 1. The coaming 1 is provided with a pair of lateral longitudinal runways 2 and a pair of lateral storage or stowage ramps 3. Each ramp 3 is positioned just above or below a space 4 provided for stowing or storing the plurality of hatch-cover sections when they are positioned vertically i. e. in the open condition of the hatchway, as will be explained hereafter.

The hatch-cover arrangement comprises a plurality of sections, elements or panels 5a, 5b, 5c, etc. provided with supporting rollers 6a, 6b, 6c, etc. rolling on the runways 2. All these hatch-cover sections, except the first or leading one 5a which is the farthest from the stowage space 4, are provided at one end, for example at 7b, 7c, etc. with a pair of rollers adapted to be engaged by an operating rope 8. The free end of this rope is secured at 9 to the remotest or leading end of the first section 5a. Moreover, all these sections are provided with so-called tripping rollers 10 positioned at the rear ends thereof.

Each pair of adjacent sections are provided on each lateral side with an interconnecting link 11. Each link has its front end pivoted on the rear end of the leading section of the pair, i. e. the section which is remotest from the stowage space 4 in the pair considered, for example in close vicinity of, or coincident with, the relevant tipping roller 10, whilst the rear end of the link is pivoted on the other section of the pair at a point 12 substantially intermediate the section length, as shown.

The operating rope 8 passes over a sheave 13 and thence to a derrick or like mast (not shown). A stationary stop member 14 may also be provided to prevent the various sections of the hatch-cover from moving when stowed vertically.

Finally, locking means such as hook members 15 (Fig. 3) may be provided for anchoring the first or leading section 5a to the preceding section 5b.

The operation of the hatch-cover arrangement described hereinabove is extremely simple. Assuming firstly that the sections are in their closed positions (Fig. 1) it will be readily understood that when the operating rope 8 is pulled in the direction of the arrow F₁ the hatch-cover assembly will move bodily along their runways 2 in the direction of the arrow F₂. This movement will cause the rearmost section, in the example shown the section 5d, to rise up the ramp 3 and, due to the pull exerted by the rope in the direction F₁ and through the engagement of the tipping roller 10d with this ramp 3, the section 5d will be tilted in the direction of the arrow F₃ and finally stowed in the position shown in Fig. 2. The link 11c carries along automatically the next section 5c pulled jointly by this link and by the operating rope 8, until it reaches the vertical position in which it is shown in Fig. 2.

In this figure also the section 5b is shown during its upward or tilting movement to its vertical position. In this example the tipping roller has its axis coincident with the pivot axis of the link 11c and rolls up the stowage ramp 3 while the next link 11b of the train of elements exerts a thrust in the direction of the arrow F₄; it is evident that this movement is assisted by the pull exerted

by the operating rope 8 on the pair of rollers 7b provided on the section 5b. Finally, the last section 5a (in the direction of stowage) is also tipped to the vertical, as shown in Fig. 3, its tilting movement in the direction of the arrow F₅ being illustrated in chain-dotted lines in this figure.

Figure 4 shows more in detail and in vertical cross-section on the one hand a section 5 (which may be any section of the assembly) provided with a pin 19 having journalled thereon a link 11, and on the other hand the stowage ramp 3 provided with a complementary retaining member 16 to prevent the tipping roller 10 disposed in a plane at right angles to the section 5 and coincident, in this specific case, with the pivotal attachment of the link 11, from moving out of engagement with the ramp 3.

The modified embodiment depicted in Figs. 5 and 6 differs from that described hereinabove only through the operating means employed. In the preceding example a rope actuated from the usual derricking or like mast of the ship was used, whilst in the case now considered the hatch-cover assembly is operated through an endless rope 17 guided by means of sheaves 18, 19 and 20 and wound on the drum of a winch 21 actuated from any suitable source of energy, for example electric power. To facilitate the operation of this assembly each section is provided with additional tipping rollers 22a, 22b, 22c and 22d. The section remotest from the stowage space 4 is provided with an additional link 23 having one end 24 pivoted on the section at an intermediate point thereof and its other end 25 provided with a roller adapted to engage the runway 2 of the hatchway coaming 1 and anchored to the operating rope 17, as shown.

The operation of this modified arrangement is obvious. When the rope 17 is actuated in the direction of the arrow F₆ the various sections are tilted one by one to their vertical positions, as shown in Fig. 6. To close the hatch-cover assembly, the operating rope 17 is moved in the opposite direction, as indicated by the arrow F₇, and the first or leading link 23 will drive the assembly to the closing position shown in Fig. 5.

Of course, many modifications may be brought to the forms of embodiment shown and described herein, as these should not be construed as limiting the scope of the invention but are given for the purpose of illustration only.

What I claim is:

1. In ship's hatches, railway waggons and the like comprising an opening with longitudinally extending lateral parallel guideways flanking the opening formed by plane surfaces and constituting a straight open rolling path, a cover arrangement comprising a plurality of separate cover sections adapted to ride on said guideways and to spread over said opening while forming an unbroken sheet over said latter, rolling means mounted on the edges of

said sections in rolling engagement with said guideways, said rolling means resting on said guideways by the virtue of the weight of the corresponding section and freely rolling thereon to close and open said opening, a stowage space at one end of said opening with lateral longitudinal runways for locating said sections in the folded condition when the hatch is open, said sections resting in said stowage space in a vertical position and substantially on an edge, rigid link means for pivotally interconnecting any two separate and adjacent sections and transmitting operating thrusts and tractions, pivot means connecting each of said link means at one of its ends to the rear end portion of the section of said pair which is remotest from the stowage space, and at a substantially intermediate portion of the other section of the pair, said sections resting in said stowage space on the said runways by means of said pivot means which belong to the rear portion of the relevant sections, and rope means connected at least to the section which is remotest from the stowage space for ensuring the control of all said sections.

2. A cover arrangement according to claim 1 wherein the control rope means is situated along the lateral sides of said opening, tipping means on each section situated between said roller means and ramp means between the end of said guideways and said stowage space for positive cooperation with said tipping means for ensuring the beginning of the lifting motion of each section.

3. A cover arrangement according to claim 1, wherein the control rope means extend over the said opening, guiding rollers for said rope on said sections except on the remotest from the said stowage space, said rollers being situated at the end of said section which is the remotest from the stowage space, and a further fixed roller over said stowage space for guiding said rope, which latter exerts a certain vertical thrust on each of said sections when opening the hatch.

4. A cover arrangement according to claim 2, comprising a complementary link means having one end pivoted on the intermediate portion of the section remotest from the stowage space and the other end provided with rollers engaging the said longitudinal edges of the hatch and being anchored to said endless rope means.
